UNITED STATES PATENT OFFICE.

JACOB S. ROBESON, OF CAMDEN, NEW JERSEY.

PYRITES BRIQUET AND PROCESS OF MAKING SAME.

1,013,614.

Specification of Letters Patent.

Patented Jan. 2, 1912.

No Drawing.

Application filed December 7, 1905. Serial No. 290,793.

To all whom it may concern:

Be it known that I, JACOB S. ROBESON, a citizen of the United States, and a resident of Camden, New Jersey, have invented a 5 Pyrites Briquet and Process of Making the Same, of which the following is a specification.

My invention relates to the treatment of 10 relatively fine particles of sulfur-bearing material for the purpose of facilitating the handling of the same in the commercial arts.

Among the most common form of sulfur-bearing materials known, are the iron pyrites and cupreous pyrites from which sulfur is recovered as such or as sulfur dioxid, 15 by the usual roasting operation. It is desirable to form the fine particles of such pyrites, or what is known as "pyrites fines" into lumps or masses, commonly termed bri- 20 quets, for convenience in roasting or burning. Numerous methods have been proposed for briquetting fine particles of sulfur-bearing material, notably iron-pyrites, and binders of various materials have been em- 25 ployed with more or less success. In general, however, the binders have added materially to the cost, or imported into the block or briquet elements which hinder the free elimination of the sulfur therefrom; 30 and they are not moisture resisting.

My invention consists in forming the relatively fine particles of sulfur-bearing material, including iron pyrites and cupreous pyrites, which are commonly termed "pyrites 35 fines" or "pyrites smalls", which cannot be handled commercially, into blocks or briquets, preferably by combining them with waste sulfite liquor as a bonding agent. The amount of sulfite liquor employed need only 40 be such quantity as will render the whole mass sufficiently plastic to permit of its being molded into the desired shape or form which is subsequently dried or baked.

My invention consists further of a non- 45 hydroscopic briquet of sulfur-bearing material united and briquetted by a binder having sufficient sulfur to combine with the bases contained in it, and, therefore, incapable of absorbing any of the sulfur dioxid 50 liberated in burning the briquet; preferably also, this binder is capable of yielding some sulfur to add to that yielded in burning the briquet.

The briquet forming the subject of my in- 55 vention is composed of relatively fine par-

ticles of sulfur-bearing material, which material may include "pyrites fines" or "pyrites smalls", and a binder, preferably consisting of the waste liquor resulting from the manufacture of paper pulp from wood and other fibers by the action of boiling such fibers under pressure in a solution of an acid sulfite. By preference I employ a vacuum concentrate of this liquor made in accordance with the process set forth in my Patent No. 833,634, dated October 16, 1906, in which is set forth a method of treating this raw waste liquor by rendering it substantially neutral with the aid of milk of lime or other suitable alkaline material and then quickly concentrating such neutralized body *in vacuo* without decomposition, to a desirable density. I have discovered that the use of such sulfite liquor as a bonding agent for the relatively fine particles of sulfur-bearing material, including iron pyrites and cupreous pyrites, produces a non-hygroscopic briquet exceedingly hard and not liable to disintegration by handling or exposure to a moist atmosphere. My improved briquets 75 not only resist the action of moisture, but actually repel it, and those made in accordance with my invention have retained their normal size and shape for all substantial and practical purposes, after remaining in 80 water for a period of from one to ten days. The burning of briquets made in accordance with my invention, therefore, is more readily accomplished since they do not absorb water in transportation or storage and therefore 85 the amount of water to be driven off during the roasting operation is so greatly reduced as to require less fuel in accomplishing the result desired, viz., the free elimination of the sulfur from the non-sulfur content of 90 95 the material.

Inasmuch as the waste sulfite liquor contains a quantity of sulfur compounds retained from the original liquor employed in making the cellulose pulp, briquets made 100 from sulfur-bearing material and this liquor as a bonding agent, are richer in sulfur than those in which a non-sulfur bonding agent is employed. The sulfur in the sulfite liquor is about double the amount 105 of that required to saturate the bases it contains after such combustion as will destroy its organic matter. The other ingredients of the binder being of a carbonaceous or other highly inflammable nature readily 110

consumed during the burning operation, render this agent ideal for the purpose of bonding briquets of sulfur-bearing material including ferrous and cupreous pyrites.

5. Sulfite liquor as ordinarily prepared contains some calcium sulfate and calcium sulfite in addition to its characteristic organic sulfonate of calcium, and these bodies contribute to its binding action. Since they 10 contain enough sulfur to saturate their base they do not absorb sulfur dioxide from the pyrites in burning.

In preparing the briquets in accordance with my invention, the sulfur-bearing material, which may include "pyrites fines" or "pyrites smalls", is preferably mixed in any suitable manner with the addition of so much of the sulfite liquor as will render the mass sufficiently plastic to permit of 20 its being molded to the desired shape or form, which amount of such liquor will vary, depending upon the size of the particles employed, the apparatus and the manner of mixing. The plastic mass so made 25 is then pressed into blocks or briquets of the desired shape and size, and preferably dried by the agency of heat, or baked in a suitable oven. When dry or relatively so the briquets are ready for use.

30. Although I have described my improved briquet and the process of making the same with especial reference to pyrites, it will be understood that my invention includes and the claims hereinafter set forth are broad 35 enough to cover, the bonding together of any form of sulfur-bearing material, including "pyrites fines" or "pyrites smalls", whether of a ferrous, cupreous, nickeliferous or other analogous composition, as well as 40 any material composed mainly of metallic sulfids such as sulfid of iron, with a binder such as sulfite liquor comprising enough or more than enough sulfur to combine with

the bases present in such binder or present as impurities in the material briqueted. 45

I claim:

1. The process herein described of preparing "pyrites smalls" for desulfurization, said process consisting in moistening the "smalls" with the liquor resulting from the 50 manufacture of sulfite cellulose pulp, and then forming the moistened mass into briquets.

2. The process herein described of preparing "pyrites smalls" for desulfurization, 55 said process consisting in mixing the "smalls" with a quantity of concentrated liquor resulting from the manufacture of sulfite cellulose pulp, and then forming the 60 mass into briquets.

3. As a new article of manufacture, a non-hygrosopic briquet of sulfur-bearing material, bonded by sulfite liquor.

4. As a new article of manufacture, a non-hygrosopic briquet of "pyrites smalls", 65 bonded by sulfite liquor.

5. The briquets herein described, containing pyrites, calcium sulfate and calcium sulfite.

6. The process herein described of preparing sulfur-bearing material composed mainly of metallic sulfids, said process consisting in moistening such sulfur-bearing material with a binder, said binder comprising a mass of sulfite waste liquor and containing at least sufficient sulfur to combine with the bases therein, and then forming the moistened mass into briquets. 70 75

In testimony whereof I have signed my name to this specification, in the presence 80 of two subscribing witnesses.

JACOB S. ROBESON.
